UNITED STATES PATENT OFFICE.

WILLIAM E. FOWLER, SR., OF CHICAGO, ILLINOIS, ASSIGNOR TO THE FOWLER CAR COMPANY, OF CHICAGO, ILLINOIS, A CORPORATION OF ILLINOIS.

RAILWAY-CAR.

1,157,304.

Specification of Letters Patent. Patented Oct. 19, 1915.

Application filed November 16, 1914. Serial No. 872,345.

To all whom it may concern:

Be it known that I, WILLIAM E. FOWLER, Sr., a citizen of the United States, and resident of Chicago, in the county of Cook and State of Illinois, have invented certain new and useful Improvements in Railway-Cars, of which the following is a specification.

My invention relates to railway cars and has particular reference to a novel means for providing an intermediate deck in a freight car.

It is common practice to provide an intermediate deck by means of which an additional load of bulky material may be carried by a single car. For instance, in the transportation of automobiles from the plant of manufacture it is common to load the chassis on the main floor of the car, then to provide a deck upon which the bodies and miscellaneous parts are loaded. This result is commonly secured by nailing stringers to the sides of the car, then laying a floor on such stringers. However, this results in damage to the car sides, is inconvenient and costly, and does not provide for the general utilization of such means.

An object of my invention is to provide means whereby an intermediate deck may be installed quickly and cheaply, and which may readily be dismantled without damage to the car's sides.

The invention will be more readily understood by reference to the accompanying drawings, wherein:

Figure 1 is an elevation partly in section of a railway box car having my improvement applied thereto; Fig. 2 is a section on the line 2—2 of Fig. 1; Fig. 3 is an enlarged fragmentary elevation of the specific means contemplated hereby; Fig. 4 is a section on the line 4—4 of Fig. 3; Fig. 5 is a view similar to Fig. 3 except in that the method of laying the floor is somewhat modified.

Referring more particularly to the drawings it will be seen that a car to which my invention may be applied may include a floor 10, side walls 11, and roof 12. The ends may consist of doors 13, or may be of the usual solid construction. Preferably the construction is applied to a car of the Fowler single sheath type, that is, a car having a metal skeleton and a single interiorly located sheathing composed of boards placed edge on edge and running longitudinally of the car.

Within the side walls 11 are mounted pockets 14, preferably in the form of castings, the inner face of which is located substantially flush with the inner face of the car side. A portion of the pocket projects outside of the plane of the wall a distance substantially equal to the projection of the metal posts on the outside of the wall. These pockets may be suitably bolted or riveted to the wall. A trunnion or pivot 15 is carried by the pocket, this pivot extending longitudinally of the car and carrying a bracket 16. The bracket is provided with an elongated aperture through which the pivot pin extends, this being provided to facilitate the swinging of the bracket. The bracket is provided with a downwardly-extending foot 17, which, in the operative position of the bracket, lies against a lower flange of the pocket and provides a rigid support for a stringer 18 which may be located thereon. It will be seen therefore that as inasmuch as the bracket has a horizontal portion which lies on the wall and a vertical portion which lies against the wall, the carrying capacity of the bracket is independent of the pivot thereof. The bracket, in effect, hooks onto the wall, but is so constructed as to fold into the pocket and out of the plane of the inside of the wall when necessary. A horizontal portion 19 of the bracket is apertured to accommodate a bolt 20 passing through the bracket and the stringer 18; thus the wooden member is secured without the necessity of nailing the same to the side of the car. A floor 21 may be located on the stringer, as shown in Figs. 3 and 4.

When the deck is to be taken out the stringers and floor are removed and the brackets 16 may then be swung backward into the pockets assuming the position of the dotted lines in Fig. 4. In that position the brackets are out of the way and can not accidentally swing into the interior of the car. The elongated pivot pin opening in the bracket provides for the locking of the bracket within the pocket, it being necessary to bodily lift it before it can be swung out of the pocket.

In the construction shown in Fig. 5 the pocket and bracket are the same but the supporting members 22 corresponding to the sills 18 are extended transversely of the car and are fitted between the vertical flanges 23 of the bracket and held in place by means

of a bolt 24. In that construction the floor 25 may extend longitudinally of the car instead of transversely.

Obviously the construction is capable of 5 considerable modification, and such modifications as are within the scope of my claims I consider within the spirit of my invention.

I claim:

- 10 1. In a railway car, the combination of walls, brackets pivoted in said walls, each of said brackets being composed of an angular member provided with a horizontal and a vertical portion, said horizontal and vertical portions lying upon and against the wall respectively and sustaining a load independent of the pivot therefor, substantially as described.
- 15 2. In a railway car, the combination of a wall having an opening therein, a bracket

Copies of this patent may be obtained for five cents each, by addressing the "Commissioner of Patents, Washington, D. C."

mounted for pivotal movement in said opening, said bracket having a horizontal portion adapted to rest upon the floor of said opening, and a vertical portion adapted to lie against the wall adjacent to said opening whereby a load is sustained by said bracket independent of the pivot, substantially as described.

25 3. In a railway car, the combination of a wall having an opening, a metal pocket set 30 in said opening, and a bracket pivoted in said pocket, the pivotal connection permitting limited bodily movement of the bracket, whereby said bracket may be locked in said pocket, substantially as described.

WILLIAM E. FOWLER, Sr.
